[57] ABSTRACT

A heat exchange device comprising a heat conducting elongated first member such as a plurality of tubes, a plurality of spaced heat conducting primarily two dimensional second members which may be flat fins having openings through which these members extend, a spacer flange at each opening integral with each second member positioned against a first member for joining the fin and thus the second member to the first member, the spacer flange having an edge bearing against another second member to maintain the spaced relationship therebetween and means forming a recessed section in the flange edge adjacent this other second member to provide space for a joining composition such as a solder and for the escape of reaction products of the joining operation whether these products are gases, liquids or solids.

FIG. 3

FIG. 2

FIG. 4

HEAT EXCHANGE DEVICE

BRIEF DESCRIPTION OF THE DRAWINGS

FIG. 1 is a fragmentary perspective view of a portion of a fin and tube heat exchanger embodying the invention.

FIG. 2 is a sectional view taken substantially along line 2-2 of FIG. 1.

FIG. 3 is a fragmentary side elevational view of a heat exchange tube showing a plurality of the adjacent fins in partial section.

FIG. 4 is a perspective view illustrating the relationship of a tube and a fin.

DESCRIPTION OF THE PREFERRED EMBODIMENT

In the illustrated embodiment the heat exchange device 10 is of the tube 11 and fin 12 construction. As is customary there are a plurality of the tubes 11 of which only two are shown in FIG. 2 arranged in parallel spaced relationship. There are also provided a plurality of spaced fins arranged parallel to each other and transverse to the tubes 11. Each fin 12 has a spacer flange 13 struck therefrom and surrounding the opening 14 through which the tube 11 extends. Each flange has an edge 15 bearing against the next fin 12 as shown in FIG. 3 to maintain the desired spaced relationship between the fins. Each flange is also positioned against a tube for providing efficient heat transfer between the tubes and the fins. Each of the spacer flanges 13 is formed with a recessed edge 15. Each flange edge 15 is formed with a recessed section 16 adjacent the next flange 12 in order to provide space for a joining composition such as a solder as illustrated at 17 in FIG. 3. These recessed sections or spacers not only facilitate metallurgical joining of the heat exchange device components but also provide an area through which the by-products of the joining reaction may escape whether these by-products are liquid, solids or gases.

In one embodiment as illustrated each first heat transfer member or tube 11 is oval in cross section and each flange 13 is similarly oval. Each flange edge 15 is provided with a plurality of recessed sections 16, here shown as two, with the two sections being located on opposite sides of the flange. Thus with this arrangement each flange 13 provides a pair of opposite end edge sections 18 to provide the proper spacing of the adjacent

fins from each other and a pair of elongated opposite recesses 16 for providing a firm joint.

The joining materials that may be used are any of those customarily employed in fin and tube heat exchangers.

Having described my invention as related to the embodiment shown in the accompanying drawings, it is my intention that the invention be not limited by any of the details of description, unless otherwise specified, but rather be construed broadly within its spirit and scope as set out in the appended claims.

I claim:

1. A heat exchange device, comprising: a heat conducting elongated first member having an elongated transverse cross section; and a plurality of thin, spaced, heat conducting, primarily two dimensional second members each having an opening through which said first member extends, said openings being complementary in cross section to said first member, each said second member further defining an integral spacer flange extending about each said opening projecting transversely thereto and positioned facially against said first member, said spacer flange having a distal edge substantially bearing against another said second member to maintain the spaced relationship between said second members, each said flange defining a long portion extending in the direction of elongation of said elongated cross section of the first member provided with a recess in the distal edge portion thereof opening toward said other second member for occupancy by a joining composition for said first and second members.

2. The device of claim 1 wherein there are provided a plurality of said elongated first members in the form of tubes so that the device constitutes a fin and tube heat exchanger.

3. The device of claim 1 wherein each said spacer flange surrounds a said first member in contact therewith, and each said flange defines a second such long portion opposite said first said long portion and provided with a second such recess.

4. The device of claim 3 wherein each said first member is oval in cross section, each said flange is oval in cross section parallel to the second member from which it projects, and a pair of said recesses are provided in each flange one each in the long sides of the oval.
